UNITED STATES PATENT OFFICE

GEORGE EDWARD THOMAS EYSTON, OF LONDON, ENGLAND, ASSIGNOR TO POWERPLUS
(1927) LIMITED, OF LONDON, ENGLAND, A COMPANY OF GREAT BRITAIN

ROTARY PUMP MACHINE

Application filed June 23, 1930, Serial No. 463,113, and in Great Britain July 18, 1929.

This invention comprises improvements in and connected with rotary pump and like machines and is more particularly concerned with constructions of the kind comprising a 5 piston body mounted within an outer rotary cylinder or drum and adapted, while revolving, kind and to enable the revoluble-reciprocatory motion back and forth across the space of the cylinder or drum.

10 The object of the invention is to provide improved constructions of machine of this kind and to enable the revoluble-reciprocatory piston to be controlled in its peculiar movements in a reliable and efficient manner.

15 According to this invention, the piston is adapted to be reciprocated back and forth in the pumping space of the outer cylinder or drum, by forming it with a circular track which is adapted to have rolling engagement with a cam or shaft mounted eccentrically in the machine. Or conversely, the piston might be provided with a cam or shaft and the circular track provided in the casing of the machine. The construction en-

20 ables control of the piston to be effected in a reliable manner and the rolling contact parts may be such as to take up centrifugal force or other stresses substantially without friction, giving considerable advantage in the

25 efficient working of the machines and enabling the piston parts to be made of robust construction. The cam or shaft would suitably be of a diameter equal say to about half the reciprocatory travel of the piston and the

30 track twice the diameter of the cam or shaft. It is convenient to have the cam or shaft operative within the circular track and to provide flats on the interior of the rotary outer cylinder or drum for the travel of the piston,

35 and it will be seen that rotation of the cylinder will cause regular reciprocation of the piston with respect to the flats provided that the cam or shaft is always in contact with the interior wall of the centric track and no slip occurs. Slip is only likely to take place at low speeds and it may be prevented by interposing a bush or a roller between the cam or shaft and the interior of the track. Or, as an alternative, the piston may have a slotted 40 portion or be formed with guides adapted to

be engaged by an offset part or extension of the cam or shaft. In order to overcome any dead positions in the drive a suitable gear or part of a gear may be provided between the cam or shaft and the track. Thus, reliable 55 starting and positive working of the machine may be ensured under all conditions. Relief of the cams or shafts from centrifugal force effects, and balance of the machine at all speeds, may be attained by providing the machine with a plurality of pistons displaced circumferentially one with respect to another. There may, for instance, be three pistons, two parallel to each other and arranged in end compartments of the cylinder or drum, and a 60 single piston equal in weight to the other two disposed in the central part of the cylinder and displaced 90° from the others, with a single stationary shaft extending through them all. Intake and delivery or discharge 65 of fluid is suitably made through peripheral ports disposed diametrically opposite each other in the outer cylinder or drum. The latter may be mounted to revolve centrically in an outer stationary casing also having suitable outlet ducts or ports and arrangement 70 may be made for the operative relation between the ports in the cylinder and casing to be varied so as to alter the phasing of the machine or the time at which entry or exit 75 of fluid takes place. This may be effected, for example, by making the eccentric cam or shaft bodily adjustable about the axis of the cylinder or drum. The piston may be of 80 lenticular type and its tips movable in engagement with raised flats on the outer cylinder or drum or it may be of other forms, for example cylindrical. In some cases it may have extensions to increase the pumping or 85 working capacity. The rotary movement of the piston is conveniently effected through the drum which may have drive parts engaging the piston. It is possible, however, to adopt the reverse arrangement and drive the outer cylinder from the piston, for instance, if the cam or shaft aforesaid were of suitable 90 diameter it could be made to rotate about its own center and positively reciprocate the piston and to revolve the outer cylinder or drum. Or both the cylinder and the cam or 95 100

shaft may be revolvably driven in opposite directions and in that case increased pumping performance is obtainable.

In order to enable the invention to be readily understood reference is directed to the accompanying drawings in which:—

Figure 1 is a more or less diagrammatic transverse sectional view of one construction of rotary pump machine in accordance with these improvements.

Figures 2 and 3 are similar views illustrating modifications.

Figure 4 is a central longitudinal section, with parts in elevation, of another construction of rotary pump machine.

Figure 5 is a transverse section, on the lines V—V of Figure 6, of a further modified form of machine.

Figure 6 is a sectional elevation of the same machine, the section being on the line VI—VI of Figure 5.

Figure 7 is a view, partly in section on line VII—VII of Figure 6, illustrating means for adjustment of the eccentric shaft in Figures 5 and 6.

Figures 8 to 11 indicate diagrammatically successive phases of operation of the machine illustrated in Figures 5 and 6.

Figure 12 is a longitudinal section of one end of a machine embodying an improved form of drive.

Figure 13 is a cross-section giving an end view of the gearing in Figure 12, and

Figure 14 is a view of the port arrangement of Figure 12.

In the machine shown in Figure 1 the piston *a* is of lenticular form and operates in an outer cylinder or drum *b* which in turn is mounted to revolve concentrically with appropriate working clearance, in an outer casing *c*. The piston is adapted in its operation not only to revolve with the cylinder *b* but also to reciprocate to and fro in the pumping space *d* as will be described. The cylinder *b* as shown, has flats *e* raised from the general contour of its interior surface and the piston *a* has flattened tips adapted to engage and move along these flats as the piston reciprocates. The reciprocation of the piston may be effected by providing the machine with an eccentrically mounted stationary cam or shaft *f*, which is of a diameter equal to half the travel of the piston, and by forming the piston with a centric track or hole *g* of twice the diameter of the shaft. The cam or shaft *f* is preferably arranged immediately above or to one side of the axis *b'* of the cylinder *b* but this is not essential though it is the simplest arrangement.

In operation, drive may be imparted to the cylinder or drum *b* for example by gearing such as *h* seen in Figure 4 hereinafter described, and as the cylinder revolves, it will be understood that owing to the eccentric and

stationary disposition of the cam or shaft *f*, the piston will be caused to reciprocate to and fro in the pumping space *d* along the flats *e*, while it is being carried round by the engagement between the flattened tip of the piston and the flats *e*. In effect, the track *g* of the piston rolls with the piston, round the cam or shaft *f* and the contact between the two, which is a rolling one, constrains the piston to reciprocate. This will be apparent if reference is also made to Figures 2 and 3 which show a similar piston in different positions of revolution. The travel of the piston is equal to twice the diameter of the shaft as will be evident and the flats *e* are made equal in extent to this travel plus the length of the flattened tips of the piston. Thus, the latter may practically fully exclude air from the pumping space *d* at the outer end of its travel assuming that the sides of the piston, as shown, are given the same curvature as the interior of the cylinder. Intake and delivery of air is suitably through diametrically opposite ports *k* in the cylinder. The outer casing *c* has inlet and delivery connections *l*, *m*, respectively on opposite sides and there will be one intake to the pumping space *d* of the cylinder *a* from the connection *l* and delivery from such space through the connection *m*, past each port *k* of the cylinder during each revolution of the latter, or in other words intake and delivery will take place from the pumping space twice in each revolution of the machine.

It will be seen that the stationary cam or shaft *f* takes the centrifugal load on the piston and that as the contact between the cam or shaft and the interior of the piston is a rolling one, friction in the control of the piston is reduced to a minimum. Slip between the cam or shaft *f* and the track *g* which might be likely to take place at low speeds, may be prevented by interposing a crescent-shaped bush *n* in the space between the cam or shaft and the track, this bush being fitted so as to rotate with the piston around the cam or shaft. It will be observed that as the centrifugal force is taken by the cam or shaft, the bush is not subject to this stress so that it revolves with minimum of friction. The clearance between the bush and the track *g* and shaft *f* is, of course, exaggerated in Figure 1. As an alternative to the bush a pin or roller *o* may be inserted between the parts as shown in Figure 2 and be adapted to roll round the cam or shaft as the piston revolves. In each case, positive engagement between the cam or shaft and the track *g* can be maintained at all times with minimum friction and slip between the parts wholly or substantially avoided. Thus reliable starting of the machine may be ensured under all conditions. In order to overcome any dead positions in the drive the inter-engaging parts *f* and *g* might be provided with gear teeth as seen in Figure 3.

In the construction illustrated by Figure 4, provision is made whereby the stationary eccentric shaft of the machine, marked f' , may be relieved of centrifugal stresses and balance of the machine preserved. This is attained by using a plurality of the lenticular pistons and balancing them one against another. Three pistons a , a' , a^2 are shown, the two outer ones, a , a^2 being parallel to each other and arranged in end compartments d' and the other a' , equal in weight to the other two together, being disposed in a central compartment d^2 and displaced 90° from the others. The position of the piston a' in Figure 4 corresponds with Figure 1 and of the pistons a , a^2 with Figure 3. In the construction in Figure 4, only a single eccentric shaft f' need be used extending through all the pistons and mounted on crank parts f^2 at each end in the end covers p of the machine. The crank parts f^2 would pass centrally through the ends of the cylinder or drum b , which may rotate on these crank parts and the shaft might have webs r thereon to seal with the partitions s between the different compartments of the cylinder. Driving gear h is provided for the cylinder b or the cylinder may be driven direct. Other parts of Figure 4 corresponding to the same parts in Figure 1, are similarly lettered in the two figures. If in Figure 4, bushes n or rolling parts o were used as in Figures 1 and 2, these might also be balanced one against another as described in connection with similar parts in my United States patent application Serial No. 365,648, filed May 24, 1929.

The construction of machine illustrated in Figures 5 and 6 is of the same general nature as that in Figure 4 but has modified form of the pistons and another means of maintaining the positive drive between the piston track and the eccentric shaft. It will be seen that the pistons a , a' , a^2 are of cylindrical form and they may also be provided with radial wings or extensions t corresponding to the tips of the pistons in Figures 1 and 4 and movable along flats e of the cylinder b . The latter may be a plain cylindrical body with parts necessary for defining the pumping spaces d' , d^2 , built up within it. For instance the flats e may be formed on segmental parts u secured by screws v and protruding parts w be secured at each end of the flats to fit the pistons. It is not essential to have the wings t on the pistons. If they were omitted the flats e would extend from tip to tip of the protuberances w , but it is preferred to employ the wings as they enable the pumping capacity of the machine to be increased to the extent of the spaces traversed by these wings.

The three pistons a , a' , a^2 are disposed as described with reference to Figure 4, the central piston a' of twice the weight and axial

length of the others and displaced 90° with respect thereto, being seen in full lines in Figure 5. The pumping space d^2 of the central compartment would, of course, also be displaced 90° with respect to the outer ones and similarly with the ports k of this central pumping space, exactly as in Figure 4. The pistons are adapted to be guided in their reciprocal movements by means of guide bars or rods x , which extend across the cylinder b parallel to the flats e and engage with slots or surfaces of the pistons. These guides x may also be the means of causing revolution of the pistons from the cylinder b , thus relieving the wings t of the pistons of driving effort. They are secured to the partitions s and b^{10} of the cylinder by screws or pins as at x' . The eccentric shaft f' in this construction is again mounted on eccentric stub parts f^2 and the cylinder or drum b is mounted by its ends b^{10} on anti-friction bearings y on these stub parts. The driving gear h of the cylinder is housed in a sealed compartment z in the left hand end cover p of the machine (Figure 6) and plates 1 are applied to the shaft stubs f^2 to shield the pumping spaces d' from the bearings y .

The means for maintaining the rolling contact between the shaft f' and holes or tracks g of the pistons in Figures 5 and 6 suitably comprises disc-like parts 2 mounted and formed in offset fashion on the shaft and adapted to engage in diametrically slotted piston parts 3 which extend at right angles to the guide bars x . It is seen from Figure 6 that the central piston a' has two rolling tracks g , g' because of its greater width and that the offset 2 is centrally arranged between them, the offsets for the other pistons being at one end thereof. The axis 4 of the offset lies in a plane passing through the axes 5 and 6 of the cylinder b and shaft f' respectively and it also suitably coincides with the surface of the shaft, as also does the axis 5, but on the opposite side. The offsets are made equal in diameter to the shaft to simplify assembly, though this is not essential, and they fit with suitable working clearance between the sides of the slots 3.

In operation, the bars x impart bodily rotary movement to the pistons while guiding them in their reciprocation and thus the tips of the piston wings t may be relieved of wear and stress. In the reciprocation, air is pumped through the ports k and the inlet and delivery connections l , m as before and pumping is effected not only by the piston itself but also by the wings and extensions t . The rolling contact between the tracks g , g' and the shaft parts f' proceeds as before and the positiveness of the rolling action is maintained by the offsets 2 and slots 3. The guide bars x also assist to this end. Owing to the arrangement of the bars at right angles to the slots 3, it is clear that for 130

any position of the cylinder *b* and the guide bars, there can be only one position of the slots and the rolling tracks. This will be evident if the diagrammatic views, Figures 8 and 11, showing the parts in progressive positions of operation, are considered. Driving of the cylinder *b* by the gear *h* thus causes rolling rotation of the piston tracks *g*, *g'* round the eccentric shaft *f'*, without slipping, and no bushes or gears, such as in Figures 2 and 3, are required to maintain the positive engagement.

It will be seen that in the construction of the machine shown in Figures 5 and 6, all the revolving cylinder and piston parts are of as light construction as possible to relieve stresses. An important advantage of the invention is that the machines may possess strength combined with lightness and compactness it being possible to make the weight 30 to 35 per cent less than in the lightest of previously used types giving the same performance. In all constructions there are few working parts and these may be of a robust manufacture; simplicity is obtained in manufacture, special accuracy only being necessary with parts requiring straightforward turning operations, for example no great accuracy is necessary in machining the parallel-sided slots 3 in which the offset shaft parts 2 work in Figures 5 and 6; advantageous balance of the forces acting is obtainable; there is only rolling contact between the piston and its main supporting surface, the cam or shaft; and extreme simplicity in lubrication is possible.

The lubrication may advantageously be effected as shown in Figures 5 and 6, from a main duct 7 in the shaft *f* *f'* fed by a service pipe 8 and having branch ducts, such as 9, leading to the different surfaces or parts to be lubricated. A lubricant pump 10, driven by gear 11 from the gearing *h* aforesaid, may be used for supplying the service pipe 8.

The inlet ports *l* of the machine of Figures 5 and 6 are shown extending round the casing *c* for a distance about equal to the angular distance between the opposite edges such as 12, 13 of one side of the pumping spaces, and the delivery ports have about half this extent with the leading edge suitably terminating at a distance from the inlet ports equal to about the transverse width 55 of the pumping spaces. It is advantageous in practice to be able to vary the phasing of the cylinder ports *k* with respect to the inlet and delivery ports of the outer casing *c* and for this purpose adjustment devices shown in Figures 6 and 7 may be used. One or both of the stubs *f* *f'* of the shaft *f* is fitted with means whereby the position of the shaft may be angularly adjusted about the axis of the stubs. For example, the right-hand stub in Figure 6 may be fitted with an arm 14 ex-

tending into appropriate engagement with a sleeve 15 adjustable by a screw-spindle 16 so as to vary the position of the stub angularly within the limits defined, say, by the slot 17 and key 18. In this way the position of the eccentric shaft parts *f'* is adjustable with respect to the rolling tracks *g*, *g'* of the pistons *a*, *a'*, *a*₂ and therefore the point in the revolution of the cylinder *b*, at which the pistons will reach the ends of their strokes is variable. Consequently, the ports *k* will be at different positions with respect to the inlet and delivery ports *l*, *m* respectively of the outer casing *c* of the machine, at the ends of the piston strokes and this is what is meant by varying the phasing of the cylinder ports *k* with respect to the ports *l*, *m*. The object of the adjustment is to vary the performance of the machine to suit different requirements.

In all of the constructions above described, the shaft *f* or *f'* has had a stationary or nominally stationary position and reciprocation of the pistons has been due to the revolution imparted to the cylinder *b*. Another arrangement, is to rotate both the cylinder and the shaft in opposite directions in the manner illustrated by Figures 12 and 13. In these figures the drive shaft is marked 19 and carries a gear 20 which is in driving engagement both with cylinder *b* and the stub *f* *f'* of the eccentric shaft *f'*. Drive of the stub *f* *f'* is direct from gear 20 by gear 21 fixed on the stub. The cylinder, however, is driven through gearing 22, 23 and 24. Gear 22 is meshed with gear 20 and is mounted, with gear 23, on a short lay shaft 25. Gear 24 is mounted or formed on the end *b*¹⁰ of the cylinder and meshes with gear 23. The gear ratios may be of any appropriate value and it is convenient to arrange for the stub *f* *f'* to turn at twice the speed of the cylinder, the rotation of the two parts, of course, being in opposite directions. The advantage of this arrangement is that without increasing the speed of revolution of the cylinder *b* an increased number of pumping strokes is obtained. For the speeds given the port arrangement shown in Figure 14 is employed, the ports being indicated by the same letters as are used in the constructions first described.

A converse arrangement of the rolling contact parts in the sense already stated, comprises a fixed circular track disposed eccentrically in the casing of the machine and a cam or shaft fixed centrally in a piston of circular cross-section. In this case the piston, in addition to reciprocating in the cylinder would rotate about its own axis.

I claim:—

1. Rotary pump or like machine, comprising an outer casing, a hollow member mounted to revolve in said casing, a piston body adapted to reciprocate across said member while revolving bodily therewith, said pis-

ton body being provided with a centric track, a cam member disposed eccentrically in the machine and adapted to have rolling contact engagement with said track, and an offset part associated with said cam member and adapted to engage formations of the piston body to prevent slip in the rolling contact engagement between said cam and track.

5 2. Rotary pump or like machine, comprising an outer casing, a revolute member mounted in said casing and having a transverse working space, a piston body of cylindrical form disposed in said space and having radial extensions operative in extensions of the space, and means for effecting reciprocation of the piston body in said working space by a rolling contact control as the piston body revolves bodily with said revolute member.

10 3. Rotary pump or like machine, comprising an outer casing, a cylinder mounted to revolve concentrically therein and formed with a transverse working space, parallel guides in said space, a cylindrical piston body movable in said space in said guides, radial extensions on said piston body movable in extensions of said space, and a shaft mounted eccentrically in the machine and adapted to have rolling contact engagement with a circular track of said piston body substantially as set forth.

15 4. A rotary pump or like machine comprising a revolute working chamber, a piston adapted to reciprocate in said chamber as the latter revolves, a curved surface disposed on and non-rotatably fixed with respect to said piston and a companion curved surface disposed in the machine and engaged in continuous cycloidally rolling contact by said curved surface of said piston as the latter revolves with said working chamber.

20 5. A rotary pump or like machine comprising a revolute working chamber, a piston adapted to reciprocate in said chamber as the latter revolves, a circular surface disposed on and non-rotatably fixed with respect to said piston and a companion circular surface disposed in the machine and engaged in continuous cycloidally rolling contact by said circular surface of said piston as the latter revolves with said working chamber.

25 6. A rotary pump or like machine comprising a revolute working chamber, a piston adapted to reciprocate in said chamber as the latter revolves, an internally circular surface disposed on and non-rotatably fixed with respect to said piston, and an externally circular surface mounted in the machine and engaged in continuous cycloidally rolling contact by said internally circular surface of the piston as the latter revolves with said working chamber.

30 7. A rotary pump or like machine comprising a revolute working chamber, a piston adapted to reciprocate in said chamber as the

latter revolves, a circular surface disposed on and non-rotatably fixed with respect to said piston and a companion circular surface fixed in the casing of the machine, one of said circular surfaces having a diameter half that of the other and the two surfaces engaging each other in continuous cycloidally rolling contact as the piston revolves with said working chamber.

35 8. A rotary pump or like machine comprising a revolute working chamber, a piston adapted to reciprocate in said chamber as the latter revolves, a circular surface disposed concentrically on and non-rotatably fixed with respect to said piston and a companion circular surface disposed eccentrically in the machine and engaged in continuous cycloidally rolling contact by said circular surface of said piston as the latter revolves with said working chamber.

40 9. A rotary pump or like machine comprising an outer casing, a cylinder, with a transverse working space, mounted to revolve in said casing, a piston mounted to reciprocate in said space from side to side of said cylinder, an internal surface of circular contour formed concentrically within and non-rotatably fixed with respect to said piston, and a circular cam or shaft disposed eccentrically in said casing and engaged in continuous cycloidally rolling contact by said circular surface of said piston as the latter revolves with said cylinder.

45 10. A rotary pump or like machine comprising a revolute working chamber, a piston adapted to reciprocate in said chamber as the latter revolves, a curved surface disposed on and non-rotatably fixed with respect to said piston, a companion curved surface disposed in the machine and engaged in continuous cycloidally rolling contact by said curved surface of said piston as the latter revolves with said working chamber, and means operative to prevent slip between said surfaces.

50 11. A rotary pump or like machine comprising a revolute working chamber, a piston adapted to reciprocate in said chamber as the latter revolves, a curved surface disposed on and non-rotatably fixed with respect to said piston, and a companion curved surface disposed in the machine and engaged in continuous cycloidally rolling contact by said curved surface of said piston as the latter revolves with said working chamber, gear teeth formations being provided on said surfaces to prevent slip between them.

55 12. Rotary pump or like machine comprising an outer cylindrical casing provided with peripheral inlet and discharge ports, a cylinder mounted to revolve in said casing and having peripheral ports cooperative with said ports of said casing, a piston body reciprocative between said ports of said cylinder, means for controlling the reciprocation

of the piston comprising a curved surface disposed on and non-rotatably fixed with respect to said piston and a companion curved surface disposed in said casing and engaged in continuous cycloidally rolling contact by said curved surface of said piston as the latter revolves with said cylinder, and means for adjusting the position of said companion curved surface for varying the phasing of said ports of said cylinder with respect to said ports of said casing.

13. Rotary pump or like machine comprising an outer casing, a revolute member mounted in said casing and having a transverse working space, a reciprocating piston body of cylindrical form disposed in said space with its axis extending in the same direction as the axis of said revolute member and means for controlling the reciprocation of said piston comprising a curved surface, disposed on and non-rotatably fixed with relation to said piston and a companion curved surface disposed in said casing and engaged in continuous cycloidally rolling contact by said curved surface of said piston as the latter revolves with said revolute member.

14. Rotary pump or like machine, comprising an outer casing, a cylinder mounted to revolve about the axis of said casing, a piston body adapted to reciprocate across said cylinder while revolving bodily therewith, a circular surface disposed centrically on and non-rotatably fixed with respect to said piston, a circular cam disposed eccentrically in and mounted to be revolute about the axis of said casing, said cylinder and cam being continuously revolute in opposite directions on said axis and said circular piston surface in this movement partaking of a cycloidal roll in contact with and about said cam.

15. Rotary pump or like machine, comprising an outer casing, a cylinder mounted to revolve therein and formed with a transverse working space, parallel guides in said space, a cylindrical piston movable on said guides, a circular surface disposed centrically on and non-rotatably fixed with respect to said piston, and a circular shaft disposed eccentrically in said casing and engaged in continuous cycloidally rolling contact by said circular surface of said piston as the latter revolves with said cylinder.

16. Rotary pump or like machine, comprising an outer casing, a cylinder mounted to revolve therein and formed with a transverse working space, parallel guides in said space, a cylindrical piston movable on said guides, a circular surface disposed centrically on and non-rotatably fixed with respect to said piston, parallel surfaces on said piston extending at right angles to said guides, a shaft disposed eccentrically in said casing and engaged in continuous cycloidally rolling contact by said circular surface of said piston

as the latter revolves with said cylinder and an off-set part on said shaft engaged between said parallel surfaces of said piston.

17. Rotary pump or like machine, comprising an outer casing provided with peripheral inlet and discharge ports, a cylinder mounted to revolve centrically in said casing and having a transverse working space terminating in ports at the periphery of the cylinder, parallel guides in said space, a cylindrical piston movable on said guides, a circular surface disposed centrically on and non-rotatably fixed with respect to said piston, parallel surfaces on said piston extending at right angles to said guides, a shaft disposed eccentrically in said casing and engaged in continuous cycloidally rolling contact by said circular surface of said piston as the latter revolves with said cylinder, and an off-set part on said shaft engaged between said parallel surfaces of said piston.
